UNITED STATES PATENT OFFICE

THORSTEIN DURMER, OF ASHLAND, MASSACHUSETTS

SKI HARNESS

Application filed June 10, 1931. Serial No. 543,257.

This invention relates to a ski harness, and particularly to such a device in which straps or other binders for holding the ski to the shoe are eliminated. This not only avoids the necessity of fastening and adjusting straps as required in the case of the usual ski, but produces a locking of the shoe in the ski which is not loosened or destroyed except when proper action to remove the shoe from the ski is taken.

The difficulties accompanying the attaching of the usual ski to the shoe of the skier, accompanied by the dangers resulting from the same loosening or breaking, have been serious objections to the popularity of the sport of skiing.

My invention is so designed and arranged that the ski can be fastened to the shoe by simply shoving the shoe into the spring clamp which cooperates with plates carried by the shoe to produce a close union of the shoe and ski.

In the accompanying drawings I have illustrated, and in the specification described a form of my improved ski harness which has proven highly efficient and durable in use.

Throughout the specification and drawings similar reference numerals have been used to indicate the corresponding parts.

30 In the drawings:

Fig. 1 is a view of a shoe in position on a ski.

Fig. 2 is a view of the shoe equipped with my shoe plate.

35 Fig. 3 is a plan view of the top of a ski before the shoe is inserted within the harness.

Fig. 4 is a similar view after the shoe has been inserted.

40 Fig. 5 shows a modified means of connecting the shoe and shoe plates.

I have indicated at 1 a portion of the ski, and at 2 a shoe. My ski harness consists of a pair of spring clamping members indicated at 3 and 4. Each clamping member is riveted at its rear end as at 5 to the vertically disposed flange 6 of an attaching plate 7 which is permanently fastened as at 8—9—10 to the upper face of the ski.

45 The clamping members are fastened to each other at their free ends as by the hook

and hole connection indicated at 11. This is an adjustable connection, there being several holes 11' formed in one of the clamping members in any of which the hook 11 of the opposite clamping member may be selectively entered.

55 Each clamping member carries an inwardly disposed locking pin or stud 12, the free end of which is beveled as at 13. The vertical flanges 6 of the attaching plates 7 are provided each with a clearance hole 14 aligned with said locking studs.

50 Each clamping member carries an inwardly disposed locking pin or stud 12, the free end of which is beveled as at 13. The vertical flanges 6 of the attaching plates 7 are provided each with a clearance hole 14 aligned with said locking studs.

55 Screwed or otherwise attached at either side of the shoe is a shoe plate 15. Each shoe plate 15 has a vertically disposed lateral flange 16, and each flange is provided with a locking hole 17 adapted to be aligned with the locking holes 14 in the ski plates and with the locking studs 12 carried by the clamps 3 and 4. The forward corners of 60 these flanges 16, above the holes 17, are beveled as indicated at 18.

65 In use the attaching plates 7 are first fastened to the ski. This may involve some adjustment of the plates to insure that their flanges 6 are correctly spaced; and for this purpose the attaching plates 7 are each laterally slotted as indicated at 20 to receive adjustment blocks 21. In applying the attaching plate 7 to the ski therefor, the proper 70 adjustment is first determined and the blocks 21 screwed down to the ski by means of the screws 8, after which the screws 9 and 10 are screwed in to assist in holding the plates in the proper relation.

75 When the shoe with its attached shoe plates 15 is inserted into the space between the vertical flanges 6 of the ski plates, the beveled corners 18 of the shoe plates engage the beveled corners 13 of the locking studs 12, and these studs are pushed outwardly until the holes 17 in the shoe plates are aligned with said studs whereupon the tension of the 80 spring clamping members 3 and 4 urges said studs into said holes thus locking the shoe to the ski.

85 As a modification, the shoe plates may be provided with the inserts 23 and 24 shown in Fig. 5 of the drawings. These inserts 23 and 24 are simple headed fastenings in the 90

nature of hollow screws which are incorporated in the shoe during its process of manufacture. The shoe plates are secured to these inserts by means of screws 25. The 5 screws 25 may thus be taken out and calks may be substituted thus adapting the shoe as a non-slipping shoe for walking when not skiing.

While I have shown and described my invention in its adaptation to a ski-harness it 10 will be understood that this treatment is purely illustrative and in no way limiting and that the principles of my invention may be adapted to articles other than skis, as for 15 example, snowshoes.

Similarly it will be understood that various modifications in the design of the ski plates and shoe plates and the manner of latching one to the other may also be resorted 20 to without departing from the spirit of my invention if within the limits of the appended claims.

What I therefore claim and desire to secure by Letters Patent is :

25 1. In a ski harness, a pair of adjustable plates adapted to be secured to a ski, said plates having upwardly extending lateral flanges, a pair of shoe plates adapted to be attached to a shoe sole and having upturned lateral flanges adapted to lie inside of and against said ski plates, said ski plates and said shoe plates having registering apertures, an adjustable clamp carried by said ski plates, studs carried by said clamp and adapted to enter said registering apertures in said ski and shoe plates so as to lock said ski and shoe to each other.

30 2. In a ski harness, a pair of adjustable plates adapted to be secured to a ski, said plates having upwardly extending lateral flanges, a pair of shoe plates adapted to be attached to a shoe sole and having upturned lateral flanges adapted to lie inside of and against said ski plates, said ski plates and said shoe plates having registering apertures, and a pair of spring arms carried by said ski plates and adjustably engageable with each other at their forward ends, studs carried by said spring arms and adapted to enter said registering apertures in said ski and shoe plates so as to lock said ski and shoe to each other.

35 3. In a ski harness, a pair of adjustable plates adapted to be secured to a ski, said plates having upwardly extending lateral flanges, a pair of shoe plates adapted to be attached to a shoe sole and having upturned lateral flanges adapted to lie inside of and against said ski plates, the forward edges of said flanges being beveled, said ski plates and said shoe plates having registering apertures and a pair of adjustable spring arms carried by said ski plates, studs having beveled free ends carried by said spring arms, said beveled free ends of said shoe plates engaging the beveled

free ends of said studs so as to guide the same into said apertures to lock said ski and shoe to each other.

4. In a ski harness, a pair of adjustable plates adapted to be secured to a ski, each plate comprising a slotted member and an adjustment block therein whereby the plates may be attached to the ski in proper position to receive the shoe of the wearer, said plates having upwardly extending lateral flanges, a pair of shoe plates adapted to be attached to a shoe sole and having upturned lateral flanges adapted to engage said ski plates, and means locking said shoe plates to said ski plates.

5. In a ski harness, a pair of adjustable plates adapted to be secured to a ski each comprising a slotted member and an adjustment block therein whereby the plates may be attached to the ski in proper position to receive the shoe of the wearer, said plates having upwardly extending lateral flanges, a pair of shoe plates adapted to be attached to a shoe sole and having upturned lateral flanges adapted to lie inside of and against said ski plates, said ski plates and said shoe plates having registering apertures, a spring clamp carried by said ski plates, studs carried by said clamp and adapted to enter said registering apertures in said ski and shoe plates so as to lock said ski and shoe to each other.

6. Means for detachably interlocking a shoe to a tread structure, such as a ski or the like, comprising opposed pairs of relatively rigid and relatively yieldable locking formations on the shoe and tread structure, respectively, interengageable with each other upon endwise sliding movement of the shoe and its locking formations into the zone of action of the locking formations carried by the ski or other tread structure yielding to permit the entrance therebetween of the locking formations carried by the shoe and thereafter returning to position to interlock with said shoe formations.

7. Means for detachably interlocking a shoe to a tread structure, such as a ski or the like, comprising a pair of laterally yieldable locking formations on the tread structure and a pair of relatively rigid locking formations on the shoe, said locking formations of the shoe interengageable with those on the tread structure upon endwise sliding movement of the shoe and its locking formations into the zone of action of the locking formations carried by the ski or other tread structure, the locking formations carried by the ski or other tread structure yielding to permit the entrance therebetween of the locking formations carried by the shoe and thereafter returning to position to interlock with said shoe formations.

8. Means for detachably interlocking a shoe to a tread structure, such as a ski or the like, comprising locking formations on

the tread structure including a pair of relatively rigid plates having holes therein and a pair of outwardly yieldable locking studs alined with said holes, and a pair of relatively rigid locking formations on the shoe having holes adapted to register with those of the relatively rigid locking formations of the tread structure upon endwise sliding movement of the shoe and its locking formations into the zone of action of the locking formations carried by the ski or other tread structure, the locking studs carried by the ski or other tread structure yielding to permit the entrance therebetween of the relatively rigid locking formations carried by the shoe and thereafter returning to position to interlock with said relatively rigid shoe formations.

9. In combination, a shoe having an outer sole, plates removably attached to said shoe, and plate attaching means comprising hollow thimbles headed at their inner ends and having their heads embedded in the outer sole of the shoe, and screws threaded into said thimbles and detachably fastening said plates to said outer sole.

10. In combination, a shoe having an outer sole, plates presenting sole-engaging portions and lateral portions, said plates removably attached to said shoe, and plate attaching means comprising hollow thimbles headed at their inner ends and having their heads embedded in the outer sole of the shoe, and screws threaded into said thimbles and detachably fastening the sole-engaging portions of said plates to said outer sole.

In testimony whereof I affix my signature.
THORSTEIN DURMER.
